UNITED STATES PATENT OFFICE.

JAMES FLEMING, OF MIDDLETON, GEORGIA.

CLOTHES-POUNDER.

No. 866,120.

Specification of Letters Patent.

Patented Sept. 17, 1907.

Application filed June 12, 1907. Serial No. 378,593.

To all whom it may concern:

Be it known that I, JAMES FLEMING, a citizen of the United States, residing at Middleton, in the county of Elbert and State of Georgia, have invented certain new and useful Improvements in Clothes-Pounders, of which the following is a specification.

My invention relates to clothes pounders and particularly contemplates the provision of a novel and useful structure of this character in which the clothes may be thoroughly cleaned, and in which the dirt when removed will be prevented from again entering the material.

An object of my invention is to provide within the ordinary cone base of the clothes pounder, a circular strengthening strip.

The further object of my invention is the provision of an improved relief valve, with novel and convenient means for actuating the same to relieve the suction within the cone base on the upward movement of the same from the water.

Further objects and advantages of my invention will be hereinafter fully described with reference to the accompanying drawing in which the figure is an elevation partly in the section of a clothes pounder structure in accordance with my invention.

In the practical embodiment of my invention I provide a clothes pounder comprising the handle portion 1, to the lower end of which is attached the ordinary cone base 2, the said cone 2 being provided according to my idea, with an internal circular groove formed at 3 therein for the reception of the upper conformable edge 4 of the tubular piece 5, soldered thereto and forming a support therefor. The cone base 2 is further provided with an air tube 6 extending upwardly from the face thereof substantially parallel with the reduced neck portion 7 attached to the handle 1. The air tube 6 is flared at the upper outer end to form a valve seat 8 for the reception of a valve 9 seated downwardly therein.

The pair of rigid supporting collars are preferably secured upon the handle 1, the upper collar 10 being arranged to support therein an operating bell-crank-lever 11 pivotally mounted and connected to the valve 9 by means of a connecting rod 12, in such manner that from the movement of said lever 11 toward the handle 1 the valve 9 will be raised from its seat. The lower collar 13 is arranged to support a rigid guide plate 14 through which the connecting rod 12 is slidably arranged, and between which and the valve 9 is mounted a coil spring 15 for normally holding said valve upon its seat within the air pipe 6.

The operation of the device is apparent, it being a well known fact that the suction caused by the upward movement of the pounder within the water and material, is often the cause of relodging the dirt in the clothes after the same has been pounded therefrom.

In the construction provided by my invention it will be seen that upon the downward stroke the air will pass out of tube 6 through valve 9, and upon the upward stroke the valve is held open by manual pressure upon the bell-crank-lever 11, to move the same against handle 1 and to thereby lift the valve from its seat.

Having thus fully described my invention, I claim:

The combination in a clothes pounder comprising a cone base having an air tube extending upwardly therefrom and formed at its upper end with a valve seat, of a handle connected to and extending upwardly from said cone base adjacent said air tube, a manually operable lever carried by said handle, a valve arranged to be seated upon said seat in said air tube, connections arranged between said operating lever and said valve, and means for normally holding said valve upon its seat substantially as described.

In testimony whereof I affix my signature in presence of two witnesses.

JAMES FLEMING.
